[57] CLAIM

The ornamental design for a corner disc for chain conveyors, as shown and described.

DESCRIPTION

FIG. 1 is a perspective view of the corner disc constructed according to the principles of the present invention,

FIG. 2 is a top view thereof,

FIG. 3 is a side view thereof,

FIG. 4 is a perspective view from the bottom thereof, and

FIG. 5 is a bottom view thereof.

The dotted lines shown in FIGS. 3—5 are for illustrative purposes only and form no part of the claimed design.

FIG. 1

FIG. 2

FIG. 3

FIG. 4

FIG. 5
